(21) Appl. No.: **29/483,215**

(57) **CLAIM**
The ornamental design for a skid mounted portable washroom facility, as shown and described.

(22) Filed: **Feb. 26, 2014**

DESCRIPTION

(51) **LOC (10) Cl.** **25-03**

FIG. 1 is a front perspective view of the embodiment of the skid mounted portable washroom facility, showing the walkway grates in a downward extended position;

(52) **U.S. Cl.** **D25/16**

FIG. 2 is a rear perspective view of the skid mounted portable washroom facility of the embodiment of FIG. 1;

(USPC) **D25/16**

FIG. 3 is a front view of the skid mounted portable washroom facility of the embodiment of FIG. 1;

(58) **Field of Classification Search**

FIG. 4 is a left side view of the skid mounted portable washroom facility of the embodiment of FIG. 1;

USPC D25/1, 3-4, 32-336

FIG. 5 is a rear view of the skid mounted portable washroom facility of the embodiment of FIG. 1;

CPC E04H 1/1216; A47K 11/02

FIG. 6 is a right side view of the skid mounted portable washroom facility of the embodiment of FIG. 1;

See application file for complete search history.

FIG. 7 is a top view of the skid mounted portable washroom facility of the embodiment of FIG. 1; and,

(56) **References Cited**

FIG. 8 is a bottom view of the skid mounted portable washroom facility of the embodiment of FIG. 1.
